(57) **CLAIM**

The ornamental design for a multi-color illuminated whiteboard as shown and described.

DESCRIPTION

The file of this patent contains at least one drawing/photograph executed in color. Copies of this patent with color drawing(s)/photograph(s) will be provided by the Office upon request and payment of the necessary fee.

FIG. 1 is a front right perspective view of a multi-color illuminated whiteboard showing my new design;

FIG. 2 is a rear left view perspective thereof;

FIG. 3 is a front view thereof;

FIG. 4 is a rear view thereof;

FIG. 5 is a right side view thereof;

FIG. 6 is a left side view thereof;

FIG. 7 is a top view thereof;

FIG. 8 is a bottom view thereof;

FIG. 9 is a front right perspective view of the multi-color illuminated whiteboard with the board being shown in a first color state;

FIG. 10 is a rear left perspective view thereof;

FIG. 11 is a front view thereof;

FIG. 12 is a rear view thereof;

FIG. 13 is a right side view thereof;

FIG. 14 is a left side view thereof;

FIG. 15 is a top view thereof;

FIG. 16 is a bottom view thereof;

FIG. 17 is a front right perspective view of the multi-color illuminated whiteboard with the board being shown in a second color state;

FIG. 18 is a rear left perspective view thereof;

FIG. 19 is a front view thereof;

FIG. 20 is a rear view thereof;

FIG. 21 is a right side view thereof;

FIG. 22 is a left side view thereof;

FIG. 23 is a top view thereof;

FIG. 24 is a bottom view thereof;

FIG. 25 is a front right perspective view of the multi-color illuminated whiteboard with the board being shown in a third color state;

FIG. 26 is a rear left perspective view thereof;

(Continued)

FIG. 27 is a front view thereof;
 FIG. 28 is a rear view thereof;
 FIG. 29 is a right side view thereof;
 FIG. 30 is a left side view thereof;
 FIG. 31 is a top view thereof;
 FIG. 32 is a bottom view thereof;
 FIG. 33 is a front right perspective view of the multi-color illuminated whiteboard with the board being shown in a fourth color state;
 FIG. 34 is a rear left perspective view thereof;
 FIG. 35 is a front view thereof;
 FIG. 36 is a rear view thereof;
 FIG. 37 is a right side view thereof;
 FIG. 38 is a left side view thereof;
 FIG. 39 is a top view thereof;
 FIG. 40 is a bottom view thereof;
 FIG. 41 is a front right perspective view of the multi-color illuminated whiteboard with the board being shown in a fifth color state;
 FIG. 42 is a rear left perspective view thereof;
 FIG. 43 is a front view thereof;
 FIG. 44 is a rear view thereof;
 FIG. 45 is a right side view thereof;
 FIG. 46 is a left side view thereof;
 FIG. 47 is a top view thereof;
 FIG. 48 is a bottom view thereof;
 FIG. 49 is a front right perspective view of the multi-color illuminated whiteboard with the board being shown in a sixth color state;
 FIG. 50 is a rear left perspective view thereof;
 FIG. 51 is a front view thereof;
 FIG. 52 is a rear view thereof;
 FIG. 53 is a right side view thereof;
 FIG. 54 is a left side view thereof;
 FIG. 55 is a top view thereof; and,
 FIG. 56 is a bottom view thereof.

The broken lines and unshaded areas form no part of the claimed design. The broken lines depicting the remainder of the multi-color illuminated whiteboard form no part of the claimed design.
